United States Patent

Des. 240,162
Patented June 1, 1976

240,162

DIAZO DEVELOPER APPARATUS

Paul Matwey, Binghamton, N.Y., assignor to
GAF Corporation, New York, N.Y.

Filed Jan. 17, 1975, Ser. No. 541,924

Term of patent 14 years

Int. Cl. D16—03

U.S. CL. D16—31

FIG. 1

FIG. 2

FIG. 3

FIG. 4

FIG. 5

FIG. 6

FIG. 1 is a front perspective view of a diazo developer apparatus, showing my new design;

FIG. 2 is a front elevational view thereof;

FIG. 3 is a rear elevational view thereof;

FIG. 4 is a side elevational view thereof, the opposite side being plain and unornamented and substantially the same as shown in this view;

FIG. 5 is a top plan view thereof; and

FIG. 6 is a bottom plan view thereof.

I claim:

The ornamental design for a diazo developer apparatus, substantially as shown and described.
